UNITED STATES PATENT OFFICE

ROBERT W. BAILY, OF PHILADELPHIA, PENNSYLVANIA

TRAFFIC SIGN

Application filed September 22, 1931. Serial No. 564,287.

My invention relates to the construction of traffic signs such as are used at the intersections of streets and roads and has for its object, in part, to provide for a simple and secure interengagement between a supporting device, adapted to be secured to a post, and label frames adapted to carry labels with the street names. A further object of my invention is to provide a construction of label frame which will permit of the ready insertion and withdrawal of label plates and at the same time to securely hold the label plates in position while the frames are in use and my invention consists, in part, in the construction of a supporting device in such manner as to provide for a secure interengagement of a label frame with it and, in part, in the construction of the label frame in such manner as to provide for its interengagement with the support and also to provide for the insertion and replacement of label plates while, at the same time, providing for the secure locking of the label plate in the frame while the frame is in use.

The nature of my improvements will be best understood as described in connection with the drawings, in which

Figure 1 is an elevation of a traffic sign embodying my improvements.

Figure 2 is a plan view of a similar traffic sign showing a somewhat different angular arrangement of the label frames.

Figure 3 is a sectional view taken as on the line 3-3 of Fig. 1, of the rectangular form of frame.

Figure 4 is a front elevation of a label holding frame generally similar to the frames shown in Figs. 1 and 2, but showing an upward extension from the frame for holding an additional street sign.

Figure 5 is a plan view of the label holding frame shown in Fig. 4, the indication in dotted lines showing how the upper portions of the plates making up the frame can be separated for the insertion of label plates.

Figure 6 is a cross section on the line 6-6 of Fig. 4.

Figure 7 is a cross section on the line 7-7 of Fig. 4.

Figure 8 is an elevation showing the man-

ner in which the shank of the label holding frame is inserted in the supporting device, the supporting device being partly broken away to show its internal construction.

Figure 9 is a view generally similar to Fig. 8, showing the label frame in socketed position in the holder, the holder being shown in section through the slot into which the shank of the frame is inserted, and

Figure 10 is a view showing a modification of the supporting head construction.

A indicates the frame holding device when constructed for use as a cap piece on the end of a post, while A¹, Fig. 10, shows a modification of this holding device adapted for use, for instance, in connection with a trolley pole or the like. The cap piece indicated at A can of course be set in any angular position on top of the post and should then of course be secured against angular deflection, which can, for instance, conveniently be done by a set screw, indicated at B. Where the holding device is to be attached to a pole it is conveniently made, as shown in Fig. 10, so

that the holding device will fit against one side of the pole and be clamped to it by a complementary casting B¹ fitting on the other side of the pole and held to the socket piece proper as by bolts, indicated at B²; any other convenient fastening device can of course be used to secure the supporting member in any desired position. The supporting member A or A¹ is formed with slotted openings, indicated at C, and with upwardly and downwardly extending sockets at the inner end of the slotted opening, as indicated at C¹ and C², a ledge being provided adjacent to the downwardly extending socket, as indicated at C³, to act as a support for a label frame inserted in the slot. A bolt hole D is conveniently provided, extending through the walls of the slot C and through one of these walls is made of such form and dimensions as to permit the head of a bolt inserted in the bolt hole to pass into contact with the shank of a label frame, as indicated at D¹.

The label frame indicated at E is provided with a shank E¹, which is adapted to enter the slot C of the holding device but is of less

height than the slot and the end of this shank is provided with upwardly and downwardly extending lugs, indicated at E² and E³, which are adapted to enter the upper and lower sockets C¹ and C² of the holding head or device, the upwardly extending lug being of such length that it will project into the upper socket C¹ when the shank of the frame rests upon the ledge C³ and the downwardly extending lug E³ is of such length that it will pass over the ledge C³ when the upper lug E¹ is inserted in its socket and the shank moved up in the slot, as shown for instance in Fig. 8. The method of inserting the shank in the holding device is clearly indicated in this figure and it will be seen that when the parts have been assembled the shank and its label frame is supported in horizontal position and so interengaged with the holding device that it can only be removed by reversing the movement by which it is introduced into the slot and made to interengage with the upper and lower sockets.

The label holding frame as shown is made up of two plates F and F¹. The shank E¹, being formed integral with the frame plate F and the plate F¹, has its lower edge and a portion of its outer edge secured to the plate F in spaced relation to this plate by means of rivets, as indicated at G, blocks G¹ being provided to properly space the plates making up the frame. This method of securing the plates F and F¹ together enables their upper edges to be separated to a limited extent and I provide on the inside of the upper edges on one or both of the plates F and F¹ inwardly extending lugs H, H, the upper edges of which are preferably made slanting as indicated at H¹. The plate F¹ is provided with a shank extension as indicated at F², adapted like the shank E¹ of the plate F to extend into the slot of the holding device or head, as shown in Figs. 3 and 9. I indicate a label plate which is made of proper size to be inserted in the frame.

In operation the upper edges of the frame plates F and F¹ are sprung apart, as indicated in Figs. 5 and 6, and a label plate or plates I is inserted between the plates into the space between the plates forming the frame, this insertion being facilitated by the tapered form of the lugs H. The return of the frame plates F and F¹ to normal position causes the lugs to extend over the tops of the label plates, thus locking them in the frame. The shanks E¹ and F² of the frame are then inserted in the slot C of the supporting head, the breadth of which is preferably such as will require the shanks to be pressed slightly toward each other in order to enter the slot and the lugs of the shank E¹ are interengaged with the sockets in the manner indicated in Figs. 8 and 9. It will be seen that the interengagement of the shanks of the frame plates in the slot of the holding device will effectually prevent the separation of the frame plates to such an extent as would permit the withdrawal of the label plate. It is also practicable with my construction to secure the label frame in the holding device before the insertion of the label plate in the frame by pressing the label plate down against the sloping surfaces of the lugs H to spring the upper portions of the plates constituting the label frame apart to a sufficient extent to enable the label plate to be fully inserted, the spring of the frame plates after the insertion of the label plate, bringing the fingers H back over the top of the label plate and the engagement of the shanks E¹ and F² in the slot, effectually preventing such spreading apart of the frame plates as will permit the withdrawal of the label plate.

As a further precaution against the disengagement of the frame with its holding device and also as a means for clamping the shank or shanks of the frame plates F and F¹ to one side of the slot in the holding device, I provide a bolt J, which is inserted in the bolt holes formed in the walls of the slot and through a bolt hole formed in the shank or shanks of the frame and with its head J¹ resting against the shank E¹ and then by means of a nut J² the bolt head J¹ can be drawn against the shank and the label frame firmly secured in position in the holding device.

Having now described my invention, what I claim as new and desire to secure by Letters Patent, is:

1. In a traffic sign, a label frame supporting member formed with a relatively high and narrow horizontally extending socket chamber, adapted to receive the shank of a label frame, said socket chamber having at its inner end a downwardly extending socket chamber to engage a downwardly extending lug on the frame shank and having a rear wall adapted to contact with and form an abutment for said lug, said horizontally extending socket chamber having also at its inner end, an upwardly extending socket adapted to receive an upwardly extending lug on the frame shank and having a front wall adapted to serve as an abutment to said upwardly extending lug when the frame shank is fully inserted in the socket chamber.
2. A label frame adapted for engagement with the supporting member as called for in claim 1, said frame having a shank adapted for entry into the socket chamber of the supporting member but of less height than said socket chamber, said shank having an upwardly extending lug adapted for entrance into the upper socket of the supporting member and a downwardly extending lug adapted for entrance into the downwardly

- extending socket of the supporting member, said upwardly extending lug being of such length that it will maintain its engagement with the socket when the shank rests upon the bottom of the socket chamber, said lower lug being of such length as will enable it to pass over the bottom of the socket chamber when the shank is moved upward in the socket chamber of the supporting member. 5
3. A sign holding means consisting of superimposed frames of spring metal, said frames having members rigidly held together with a space between to allow the insertion of a sign plate through one open end into said space, the members on the open end being formed with inwardly projecting rigid lugs extending from opposing members across the open space to retain said sign plate below said projecting rigid lugs. 10
4. A label frame as called for in claim 3, in which the inwardly projecting lugs on the separable edges of the frame plates are formed with sloping upper surfaces. 15
5. A label frame as called for in claim 3, in which both frame plates are provided with shanks adapted to enter a slot in a supporting device. 20
6. A traffic sign comprising a supporting member formed with a slot for the introduction of the shank of a label frame, said slot having upwardly and downwardly extending sockets at its inner ends and a ledge adjacent to the downwardly extending socket for supporting the shank of the frame in combination with a label frame having a shank of less height than that of the slot formed with an upwardly extending lug adapted to engage in the upper socket and a downwardly extending lug adapted to engage in the lower socket, said upwardly extending lug being of such length as to extend into the socket when the shank of the label frame rests upon the ledge and said lower lug being of such length as to clear the ledge when the shank is moved upward in the slot and a bolt securing the shank and supporting member in assembled position. 25
7. A sign holding means consisting of a post engaging corner piece, having one or more integral holding arms provided with a frame holding chamber having opposed walls, a sign holding frame having an end portion inserted in the holding chamber, means for rigidly clamping the sign holding frame against one wall of said holding chamber, the opposite wall being apertured to permit the insertion of the clamping means into engagement with the frame. 30
8. A sign holding means consisting of a post engaging corner piece, having one or more integral holding arms provided with a frame holding chamber, a sign holding frame having an end portion inserted in the holding chamber, one wall of said holding chamber being provided with polygonal openings 35
- arranged to permit the insertion of clamping means and prevent the rotation thereof, said clamping means comprising bolts with nuts threaded thereon, said bolts being inserted through the opposite wall and the sign holding frame to rigidly clamp said frame to the last named wall, said frame having members rigidly held together with a space between to allow the insertion of a sign plate through one open end, the members on the open end being formed with inwardly projecting lugs extending across the open space. 40
